PORTABLE BUILDING STRUCTURE

William B. Stout, Detroit, Mich., assignor, by
mesne assignments, to Stout Engineering Laboratories,
Inc., Dearborn, Mich., a corporation
of Michigan

Application November 13, 1935, Serial No. 49,463

3 Claims. (Cl. 20—2)

This invention relates generally to portable building structures. More particularly, it relates to trailers of the expandible type which may be conveniently moved from place to place by a conventional automobile, which are adapted to be unfolded when not actually in motion to provide a substantial, enclosed, building structure which may be used for living quarters.

While building structures of this generic type have heretofore been known, it is a general object of the present invention to provide an improved construction, which, when expanded to form a house, will provide a substantial type of construction and which will afford many conveniences of construction not heretofore obtainable in structures of this general class.

The present invention contemplates the provision of a building structure having a main body section which has a permanent floor, roof and end walls. The side walls of the body section are composed of a plurality of hinged panels which are pivotally secured with respect to the main body section and adapted to be folded in superimposed parallel relation with respect to each other. These panels when unfolded constitute the roof, side walls, floor and outer wall of a portion of the house. When in folded position, these members serve to provide a supporting truss for the side of the main body section to add strength to this main body section while it is being transported from one location to another.

It is a general object of the present invention to provide a trailer construction of this generic class in which the joints between the various sections are provided with sealing means which prevent the access of water or other foreign matter not only when the sections are in folded position, but also when the sections are in extended or unfolded position.

Yet another object of the invention consists in the provision of a novel, strong, light, wall construction which affords a maximum of protection, insulation and an attractive appearance, both externally and internally, and yet is relatively light in weight and easily handled.

Still further, the present invention contemplates the provision of a construction which may easily be folded to provide a light weight, compact and neat appearing trailer structure which may be easily and conveniently transported from place to place by means of a conventional automobile.

Yet another object of the present invention consists in the provision of an expandible building construction which, in its unfolded condition

will afford substantially increased floor space and yet which will be of very stable and rugged construction.

The present invention further contemplates the provision of a transportable structure which has extensible portions constituting both sides thereof, in order that the resultant building structure, when the wall sections have been completely unfolded and secured in position, will be substantially more than twice as large as the main body section of the building when the wall sections are in folded position.

An important feature of the present invention resides in the construction and arrangement of foldable panels such that a structure for housing an automobile may be provided on one side of the central structure. The garage thus provided has no floor, the panel generally serving as floor for this portion of the structure being retained in substantially vertically disposed position and constituting a partition wall between the main body portion and the garage.

Yet another object of the present invention consists in the provision of novel means for mounting a compartment with respect to one of the pivoted wall sections in order that the compartment as a whole may be bodily swung outwardly of the main body section when the wall sections are unfolded and may be bodily swung inwardly of the main body sections when the wall sections are folded.

Yet another feature of the present invention consists in the provision of novel means for interconnecting the various wall sections making up the auxiliary portion of the house structure in order that these sections may be conveniently and compactly folded in order to provide a maximum bracing effect of the main body section and, at the same time, occupy a relatively small amount of space, as a whole.

Many other and further objects and advantages of the present invention will become apparent from the following specification when taken in connection with the accompanying drawings forming a part thereof.

In the drawings:

Fig. 1 is a perspective view of the improved portable building structure having the auxiliary side portions thereof in folded position, the structure as a whole being secured to an automobile in position for movement from place to place.

Fig. 2 is a perspective view similar to Fig. 1 showing one of the auxiliary portions of the building partially unfolded with respect to the main body portion.

Fig. 3 shows the building structure on location completely unfolded and disconnected from the vehicle by which it is moved.

Fig. 4 is a diagrammatic floor plan of the complete building in unfolded condition.

Fig. 5 is a vertical sectional view taken longitudinally on the line 5—5 of Fig. 4 showing the arrangement of the kitchen in the main body section of the trailer.

10 Fig. 6 is a fragmentary vertical sectional view taken on the line 6—6 of Fig. 5 through the kitchen compartment of the main body section looking forwardly.

Fig. 7 is a vertical transverse sectional view taken on the line 7—7 of Fig. 5 showing the arrangement of the buffet in the central portion of the main body section.

Fig. 8 is a transverse sectional view taken on the line 8—8 of Fig. 2 showing the mounting of 20 the front doors of the main body section.

Fig. 9 is a horizontal sectional view taken on the line 9—9 of Fig. 3 through the entire unfolded building structure with the auxiliary sections in completely unfolded position.

25 Fig. 10 is a vertical sectional view taken on the line 10—10 of Fig. 9 showing the frame construction of the main body section.

Fig. 11 is a front elevation with the sheathing removed showing one of the auxiliary sections in 30 completely unfolded position and showing the means for supporting this auxiliary section with respect to the main floor of the body portion.

Fig. 12 is a front elevation similar to Fig. 11 showing one of the auxiliary sections in completely folded position and the other in partly opened position, the sheathing being removed to facilitate the illustration.

Fig. 13 is an enlarged sectional view taken on the line 13—13 of Fig. 9 showing the means by 40 which the wheels are supported on the frame work of the main body section.

Fig. 14 is an enlarged sectional view taken on the line 14—14 of Fig. 13 showing the wheel mounting and wheel housing.

45 Fig. 15 is an enlarged sectional view taken on the line 15—15 of Fig. 9 showing the pivotal mounting of one of the auxiliary floor sections with respect to the floor section of the main body portion.

50 Fig. 16 is an enlarged sectional view taken on the line 16—16 of Fig. 9 showing the means by which the lower marginal edge of the outer wall panel is secured to the outer marginal edge of the auxiliary floor section.

55 Fig. 17 is a sectional view taken on the line 17—17 of Fig. 15 showing the mounting of one of the auxiliary end wall panels with respect to the main body section of the trailer and also with respect to the main and auxiliary floor sections thereof.

Fig. 18 is a sectional view taken on the line 18—18 of Fig. 16 showing the mounting of one of the auxiliary end wall panels with respect to the outer wall section and the auxiliary floor and further showing the means for locking these members in their respective positions.

Fig. 19 is an enlarged sectional view showing the manner in which the auxiliary floor sections are secured to the auxiliary end wall panels.

70 Fig. 20 is an enlarged sectional view taken on the line 20—20 of Fig. 3 showing the means by which the auxiliary roof panel is pivotally secured to the main body section of the trailer and 75 also showing the means by which this hinged

joint is sealed to prevent the access of water or other foreign matter.

Fig. 21 is an enlarged sectional view taken on the line 21—21 of Fig. 3 showing the manner in which the outer wall panel is pivotally secured 5 to the outer marginal edge of the auxiliary roof panel.

Fig. 22 is a sectional view taken on the line 22—22 of Fig. 20 showing the pivotal connection between the outer wall panel and the auxiliary 10 roof panel.

Fig. 23 is an enlarged fragmentary sectional view taken on the line 23—23 of Fig. 3 showing the means by which the removable floor supporting truss is secured to the main body section and 15 to the outer wall section.

Fig. 24 shows a modified form of the invention in which one of the extensible sections is used as a garage.

Fig. 25 is an enlarged fragmentary sectional 20 view taken on the line 25—25 of Fig. 24 showing the modified hinge construction for mounting the end panels of the extensible section when it is desired to use this portion of the structure as 25 a garage.

With more particular reference to the drawings, the specific embodiment of the invention disclosed therein comprises, in general, a main body section which is preferably formed of a frame work of relatively light weight sheet metal 30 tubing. The tubing is preferably square in cross section to facilitate joining adjacent portions thereof and to provide a substantial flat surface for the securement of sheathing thereto.

The main body section comprises a pair of substantially parallel longitudinally extending sill trusses 10. These sill trusses are formed of sheet metal tubing and have diagonal braces therein which serve to materially increase the strength and rigidity of the truss structure as a 40 whole. These longitudinal sill trusses 10 are maintained in spaced substantially parallel relation by means of transversely extending tubular members 11 which serve to join the side sill members together at suitable intervals 45 throughout their length. Slightly rearwardly of the longitudinal central portion of this main body section are mounted a pair of wheels 12 which are journaled on a suitable axle 13, which is in turn connected to the sill members by 50 means of semi-elliptic leaf springs 14. Each of the wheels 12 is provided with a brake 15 actuated by means of longitudinal pull rods 16, each connected at their forward ends by means of a pivotal link 17 to a brake booster cylinder 18. 55 The booster brake cylinder is of the fluid actuated type and is adapted to be connected by means of suitable tubing 19 to a source of power on the vehicle which is used to tow the building structure from place to place.

60 Flooring 22 for the main body section of the structure is provided, and is preferably formed of plywood or suitable similar material. This flooring is supported by the transverse sheet metal tubular members 11 and the longitudinal sill trusses 10. These transverse supporting members 11 extend laterally beyond the wheels 12 and are connected together at their extreme outer ends by means of a longitudinally extending square tubular member 24. It will thus be seen that a substantially rectangular frame work is provided for supporting the flooring of the main body section of the structure, and that the wheels 12 extend upwardly through this frame work and flooring.

At the corners of this flooring frame work the longitudinally extending members 24 and the end transversely extending members 23 are preferably reinforced by means of triangular gusset plates 25 welded to each of these members in order to provide additional strengthening at the corners of the frame. The plywood flooring is preferably covered with a layer of linoleum or suitable finish material 27.

By reference to Figs. 13 and 14, it will be seen that wheel housings comprising a frame work of sheet metal members 26 serve to provide a recess in which the wheels of the trailer 12 may be free to rotate and move a substantial distance vertically with respect to the floor.

The roof structure of the main body section of the building structure comprises a plurality of arched rafters 30 preferably formed of sheet metal of hollow section and welded at their ends to longitudinally extending members 31. Cross brace members 32 are also secured at their ends to the longitudinally extending members 31 and extend transversely across from side to side of the roof structure and form, with the rafters 30, a truss for supporting the roof proper. The roof is preferably covered by means of a sheet 33 of light weight, hard, durable, corrosion-resisting material such, for example, as a magnesium alloy, which may be secured directly to the flat upper side of the transversely extending rafter members 30. As is seen by reference to Fig. 20, this roofing material 33 has its edges carried substantially out past the longitudinal members 31 and forms an overhanging eave 34 which has a reversely bent marginal edge 34a in order to prevent the access of rain to the interior of the structure. Interior roof trim 36 is secured to the under side of the transversely extending brace members 32, and preferably has disposed inwardly thereof a sheet of insulating and sound-proofing material 37. The sound-proofing 37 may consist of any suitable material, and it has been found that felted fibrous sheets are particularly satisfactory for this purpose.

The roof structure as a whole is supported on the floor structure of the main body section of the trailer by means of a plurality of vertically extending sheet metal posts 35 of hollow cross section welded to the members constituting the flooring supports and similarly welded to the members constituting the roof framing. It will be noted by reference to Figs. 9 and 10 that the intermediate posts 35 are disposed slightly inwardly from the plane in which the end posts lie in order that the end panels or end wall structures of the panel may be folded in line with the end posts as will hereinafter be more clearly seen.

A vestibule is formed at the front end of the main body section and comprises a pair of arcuate sections of sheathing of magnesium alloy, supported on the body frame work in order to generally streamline the front end of the building and to provide a door opening in the front end thereof. These arcuate sections of sheathing 38 are preferably secured directly to the frame work and have immediately inside thereof sheets of sound-proofing material in order to provide insulation, and may be covered on their inner side by means of suitable inner trim material 39. A pair of transverse partition members 41 are disposed inwardly of the arcuate sections 38 and cooperate therewith to form suitable closets 42 on either side of the front entrance. These

closets thus formed may be closed by suitable doors 50.

A pair of arcuate doors 45 are each hinged on either side of the doorway opening, in the front end of the main body section, and are adapted to mate in their marginal edges to provide a tight closure for the front end of the building. The doors 45 may each have a suitable window 46 therein and are linked together in order that they may be simultaneously actuated. A crank arm 48 is rigidly secured to the upper marginal edge of one of the door members 45 and has pivotally connected in its outer end a transverse link 49 which extends across the door opening and is pivotally anchored in the upper frame member of the opposite door a suitable distance outwardly from the hinge thereof. It will be apparent that as one of the doors 45 is opened, the crank arm and link 49 will serve to cause a corresponding opening movement of the opposite door and, likewise, the doors will be simultaneously moved to closed position. These doors, as will be seen from the drawings, are preferably formed arcuate in order to preserve the general streamlining effect of the body as a whole and to provide a forward vestibule for the central body section of the building structure forwardly of the main portion thereof.

The frame work supporting the floor 22 of the main body section of the building is extended forwardly and is provided with a ball member 52 which is adapted to engage a suitable socket carried on the vehicle to which the building is adapted to be secured for transportation. The flooring 22 is also extended forwardly to provide flooring for the vestibule, as well as for the main body section of the building.

The rear section of the main body portion of the building is provided with a vestibule somewhat similar to the forward vestibule just described. The rear vestibule is defined by arcuate wall sections 60, similar to the arcuate sections 38 described in connection with the front vestibule, these sections, together, forming a door opening in which is hinged a suitable door 61. As will be seen by reference to the foregoing, each of these wall sections, as well as the door, is preferably comprised of a section of sheet metal sheathing secured directly to the square tubular members which form the frame work. Inwardly of the sheathing is secured a layer of fibrous sound-proofing material and the interior surface may be covered by any suitable inner trim material, as is conventional in structures of this type. It will be seen that the arcuate sections 60 provide storage space on either side of the rear door, the purpose of which will hereinafter be clearly seen.

In substantially the longitudinal central portion of the main body section, and extending across the transverse width thereof, a buffet is provided, which comprises a lower bin 65, preferably closed by means of a suitable pivoted door 66, and a pair of drawers 67 located beneath a suitable shelf 68. Additional shelves may be located on the lateral sides of the drawers 67 and a mirror 70 is mounted for transverse sliding movement at the back portion of the shelf in order that when it is in the closed position as is shown in Fig. 7, it will form an attractive closure for the back of the buffet, and when slid transversely sideways, will form an aperture through which communication may be had with the rear compartment or kitchen of the main body section. This buffet is preferably located just forwardly

of the wheel housings 26, as may be seen by reference to Fig. 10. Rearwardly of the buffet, a compact and convenient kitchen is provided, which is illustrated in detail in Figs. 4 to 7 inclusive.

- 5 In the kitchen, a cupboard 75 is formed above the buffet and is provided with a door which permits access to the cupboard from the kitchen. A series of drawers 16 are suitably mounted on top of the right hand wheel housing 26. On top of the drawers 16 is located a suitable compact gas stove 77, having an oven 78 thereabove. Cupboards 79 occupy the space above and beside the gas stove.
- 10 15 On the opposite side of the kitchen over the other wheel housing 26 is mounted a refrigerator 150, preferably also designed to be operated by gas and occupying substantially the corresponding position on the opposite side of the kitchen as is occupied by the gas stove just described. It will be appreciated that the gas stove and refrigerator are by far the heaviest of the permanent fixtures in the building and consequently their mounting directly over the wheel materially enhances the riding qualities of the structure as a whole and serves to balance the structure.
- 20 25 It has been found that the arrangement described above provides a very convenient and compact kitchen, but due to present day limitations on the transverse width of structures of this kind, it may be desirable to provide additional space between the kitchen and the gas stove. This may be accomplished by mounting the refrigerator 150 on suitable trackways 151 in order that when the building is unfolded the refrigerator may be moved bodily outwardly to provide greater clearance between it and the gas stove. Likewise, when the structure is folded for transportation, the refrigerator may be slid inwardly 30 to the position shown in full lines to permit compact folding of the structure.
- 30 35 40 45 In the storage space on the left-hand side of the rear vestibule is located a suitable gas cylinder, which may provide a suitable source of gas for the operation of both the stove and the refrigerator. Further important structural features of this kitchen will hereinafter be apparent.

- 45 50 55 60 65 70 75 In order to extend the size of the building structure to form a house when it is parked in a determined location, an auxiliary roof section 80, preferably formed of a rectilinear frame work of hollow sheet metal tubing and is pivotally secured to the roof section of the main body portion of the building in the manner shown in detail in Fig. 20. This auxiliary roof section 80 in general comprises the frame work 81, a section of stiff metallic sheathing 82 on the outside thereof, a layer of sound-proofing material 83 interiorly of the sheathing and a sheet of suitable interior trim 84 secured internally of the frame work. The longitudinal marginal frame member 81 has welded thereto hinge members 86 which are pivotally mounted in suitable brackets 87, secured to the roof structure of the main body sections. It will be seen by reference to Fig. 20 that the pivotal mounting of this hinge is in underneath the eave of the roof 33. The inner or upper marginal edge of the section of outer sheathing 82 is extended inwardly past the pivotal mounting of this hinge and is arcuately flanged to form a marginal sealing strip 88. It will be apparent that as this auxiliary roof section 80 is swung about its pivot, the flared flange 88 will come closely in engagement with the reversely bent marginal edge 34a of the overhanging eave of the roof 34.

effecting a tight seal between these two members. In order to insure the tightness of this joint adjacent this hinge, a continuous longitudinally extending flexible strip 90 serves to provide additional sealing means. This strip 90 has one of its lateral marginal edges preferably adhesively secured to the flange 88 of the sheathing 82 and has its opposite marginal edge secured permanently to the roof section 33. The flexible sealing element may be formed of leather or any suitable tough, flexible, water-resisting material. It will be apparent that this sealing strip 90 is sufficiently wide so that it may remain with its marginal edges secured to both the main roof and the auxiliary roof sections throughout all angles of pivotal movement of the auxiliary roof with respect to the main roof portion of the building.

10 15 20 It will be apparent by reference to Figs. 1, 2, and 3 that this auxiliary roof section 8 is of a length substantially the same as the longitudinal length of the main body section, and is of a width substantially the same as the height of the main body section from the eave of the roof to the floor thereof.

25 30 35 40 45 50 55 60 65 70 75 An outer wall panel 92 is pivotally mounted to the outer marginal edge of the auxiliary roof panel 80. Details of this mounting are clearly shown in Figs. 21 and 22. It will be seen that this outer wall panel, similar to the roof panel just described, comprises a rectilinear frame work 93 of sheet metal tubing of hollow cross section and a sheathing member 94 serving to brace this frame work. Sound proofing material 95 is located inwardly of the sheathing and a layer of trim material is secured to the inboard side of the frame. A plurality of brackets 97 are welded to the outer longitudinal frame member of the auxiliary roof panel and serve to provide means for mounting pivot pins 98, which pass through the terminal ends of the transverse frame members of the outer wall panel. It will thus be clear that a pivot mounting between the marginal edges of this outer wall panel and the auxiliary roof section is provided. It will be seen that the metallic sheathing 82, which provides the exterior covering for the auxiliary roof panel is carried outwardly and curved downwardly to provide an overhanging portion 97 to protect the pivotal connection between these two members. The sheathing 94, covering the outer wall section, may be extended upwardly past the pivot to provide a marginal flange which extends throughout the entire length of the outer wall panel. A resilient strip 99 is secured to the outer edge of the outer longitudinal frame member of the auxiliary roof panel which will engage with this extended flange of the sheathing 94 to provide a resilient seal for the pivotal connection between these two members when they are in the unfolded position shown in Fig. 21.

60 65 70 75 80 85 90 95 100 As will be apparent by reference to the drawings, the outer wall section is of slightly less width than the auxiliary roof section, and is adapted to be folded in superimposed, substantially parallel relation with respect thereto in order that both these members may be retained flat against the side of the main portion of the building when in folded position as shown in Fig. 1.

80 85 90 95 100 A pivotally mounted auxiliary floor section is provided at each side of the main body section. This floor section comprises a rectilinear frame work of hollow steel tubing members 101, which have secured thereto ply wood flooring 102 similar in construction to the flooring 22 described in 75

connection with the main body section. This flooring 102 may be covered with a suitable surface covering of linoleum 103, as may be desired. The inner, longitudinal member of the frame work 101 has secured at spaced intervals therealong, a plurality of brackets 105, which have tubular end portions 106, surrounding the outer longitudinal frame member 24 of the main body section. It will be seen that this construction 0 provides a pivotal mounting of the auxiliary floor section 101 with respect to the floor section of the main body portion. In order to provide a continuous floor surface between the main and auxiliary floor sections when both are disposed 5 in horizontal position, a removable strip of plywood flooring 106 is provided which is adapted to lie in the space between the auxiliary flooring 102 and the flooring 22 of the main section. It will be readily appreciated that this removable 10 strip 106 may be completely removed from its position, as shown in Fig. 15, when it is desired to swing the auxiliary flooring section vertically with respect to the main flooring sections.

In order to support the auxiliary floor section 101, with respect to the main flooring section, a removable truss section 110 is provided. The mounting of this removable truss is shown in detail in Fig. 23. This truss section is preferably formed of sheet metal tubing welded together to 5 form a strong supporting truss and has its inner end preferably provided with a portion 107 adapted to enter a suitable socket 108 on the frame work of the main body section at the longitudinal central portion thereof. The outer end 10 of this truss section 110 is secured to the lower marginal edge of the outer wall panel, as will hereinafter be described in detail.

The auxiliary sections of the building structure as a whole are adapted to be closed at their 10 ends by means of pivotally mounted end sections, each of which preferably comprises a frame work formed of steel tubing 112 and have sheathing, sound proofing material and inner trim secured thereto, in substantially the same 15 manner as has been described in connection with the pivoted panels forming the roof and outer wall panel of these auxiliary sections. The outer, longitudinal member of the auxiliary floor section 101, is secured to the lower marginal edge of the 20 outer wall panel in substantially the manner shown in Figs. 16 and 18. By reference to these figures, it will be seen that a plurality of nuts 115 are welded at spaced intervals along the outer longitudinal floor frame member 101. A plurality 25 of studs 116 have slotted, threaded inner ends, and are adapted to be passed through suitable holes in the frame members forming the framework in the outer wall panels and screwed into the stationary nut 115. It is seen that the nuts 30 115 have transverse vertically disposed holes therein and each is provided with a removable pin 117 which, when the studs 116 are screwed into position, will cooperate with the slot in the threaded end of the stud 116 to firmly lock these 35 studs in position.

By reference to Figs. 17 and 19, it will be 40 apparent that the pivotally mounted end panels are secured by means of hinges 113 to the vertical frame members of the main body section 45 35. It will be noted that each of these pivotally mounted end panels is provided around its marginal edge with a resilient strip 114, which serves to cooperate with an inwardly projecting flange 100 on the sheathing members of the adjacent 50 panel sections with which this end panel co-

operates. The projecting flanges 100 are in themselves somewhat resilient and due to their mounting provide an extremely resilient engagement with the end panels with which they cooperate consequently effecting a tight closure. 5 The lower marginal frame member of the frame work 112 has welded along its upper surface, a plurality of stationary nuts 120, which register with suitable vertically disposed holes through this frame member. A plurality of bolts 121 10 are adapted to be passed through suitable holes in the outer longitudinal frame member of the frame work 101 of the auxiliary floor section. These bolts or studs 121 extend upwardly through this frame work, through the floor and are adapted to be threaded into the stationary nuts 120 15 in the end panels.

Thus it will be seen that relatively simple means are provided for securing these end panels in position with respect to the auxiliary floor.

The auxiliary supporting truss 110 is provided at its outer end with a vertically extending flange portion 111 having an aperture therein which is adapted to receive one of the bolts 116 which 20 secure the outer wall panel to the auxiliary floor 25 section.

Both the outer wall panel and the end panel 30 may be provided with suitable windows generally designated as 125 which may be covered by suitably screening permanently secured to the sheathing and may be closed by sliding windows movable substantially in the plane of the panels.

From the foregoing, it will readily be appreciated that the building structure as a whole 35 may be folded into substantially the position shown in Fig. 1, and secured relatively simply to a suitable vehicle 126 and transported from place to place as may be desired. When a desired destination has been reached, it will be apparent that the forward end of the main body section may be supported by a plurality of suitable jacks 127, which, together with the wheels 12, will serve to maintain the main body section 40 of the structure in substantially horizontal position. The roof section 80 may then be raised from its position parallel to the side of the main body section to substantially the position shown in Fig. 2 of the drawings. The outer wall panel 93 may then be swung downwardly about its pivot and its lower marginal edge supported by a suitable pair of jacks 128. It will be clear 45 that the unfolding of these two members, due to the pivotal connection described above, effects a tight seal at the pivotal joint thereof in order to exclude water or other foreign matter. The auxiliary floor section 101 is then swung downwardly about its pivot to a substantially horizontal position. The removable truss element 110 is then inserted in place in the frame work 50 of the main body section and its outer end is secured to the outer wall panel 93 by means of one of the studs 116 which pass through this outer wall panel and into one of the stationary nuts 115 secured to the auxiliary floor section. It 55 will be seen that this auxiliary truss 110 serves to tension the frame work of the auxiliary floor section and provide with the outer wall panel and main floor section a substantially unitary construction.

The remainder of the bolts 116 are then secured 60 in place in order to firmly lock the outer wall panel with respect to the floor panel 101. As has been described above, each of these studs 116 is locked against rotation by means of inserting the removable pin 117 through the nut 75

and through the slot in the threaded end of the stud. The end panels 112 are then swung outwardly about their hinges 113 and locked in engagement with the auxiliary floor section by means of the studs 129 being threaded into the nuts 120, which, as has been described, are secured permanently to the lower frame member of the end panels. It will be seen that the weather stripping 114 engaging the flanges of the sheathing of the adjacent sections serve to provide a tight seal around the marginal edge of each of the end panels. The auxiliary section on the opposite side of the main body section may be unfolded in substantially the same way and it will, therefore, be seen that an expandible building structure is provided which has a relatively large continuous floor space interiorly thereof. The removable strips 106 may now be inserted in place, which serve to bridge the space between the floor 102 and the flooring 22 of the main body section in order to provide a continuous floor surface interiorly of the building.

It will be readily appreciated from the foregoing that the unfolding of these panels and flooring sections to provide a building structure of substantially larger area of floor space is a relatively simple operation, and that the resulting structure provided is rigid and insulated and sound-proof throughout. It will be further appreciated that all of the pivotal connections between the various panels are effectively sealed when in unfolded position in order to prevent the access of rain or vermin. Access to the interior of the building may conveniently be had by either the front door 46 or the rear door 61.

It is seen from the foregoing that the windows in the front door, the aperture in the buffet and the window in the rear door are all aligned longitudinally in order that as the structure is being transported, a clear view is obtained from end to end, consequently not interfering with the rear view of the occupants of the vehicle used to tow the structure.

When the structure is completely folded suitable bolts 152 may be passed through the lower marginal corners of the roof panel to secure this member directly to the frame in order to lock the foldable sections in firm superimposed position.

In order to provide closet space interiorly of the building structure when in unfolded condition, a permanent closet 130 may be permanently mounted on one of the pivotally mounted end wall panels. This closet may be conveniently closed by a suitable door 131 and has an arcuately extending permanent wall 132, which is supported wholly by a longitudinally extending wall 133 secured to the pivotally mounted end wall panel. The door 131 is preferably hinged directly to the auxiliary end panel on which the closet 130 is mounted. On the inner side of the wall 133, a housing 134 may be mounted, which serves to provide support for a tier of drawers 135. By reference to Figs. 4 and 5 of the drawings, it may be appreciated that a removably mounted sink and drain board 136 may also be mounted on the inboard side of the supporting wall 133 when the building structure is in unfolded condition. This sink 136 preferably has a drain 137, which extends downwardly therefrom and may pass through a suitable hole in the floor of the main body section, directly on to the ground beneath the building structure. A water tank 138 may be mounted in the space on the right hand side of the rear vestibule and may be provided with a suitable tap 139 from which water may be

drawn into the sink 136. It will be apparent that when it is desired to transport the building structure from one place to another that the end wall panel 112 must, necessarily, be swung inwardly to fold the structure. Consequently, the sink and drain pipe 136 and 137 respectively, may be removed and the end wall panel 112, carrying with it the closet 130 and the tier of drawers 135, may be swung inwardly until the auxiliary end panel 112 lies substantially parallel to the side of the main body section. It will be apparent that the closet 130 and the tier of drawers will then occupy substantially the space indicated by dotted lines in Fig. 4. This construction has been found to provide a relatively compact and convenient arrangement which affords closet space interiorly of the building structure when in unfolded condition, and bodily moves this closed compartment into the main body section of the building structure when the auxiliary sections thereof are folded 20 into position.

In the modified form of the invention shown in Figs. 24 and 25 of the drawings, a novel and different method of mounting the end panels is provided in order that one of the auxiliary sections may be used for a garage.

In this form of the invention, a continuous piano hinge 140 is used in place of the hinges 113 for securing the end panels 112 to the posts 35 of the main body section. It will be clear that the use of the piano hinge 140 permits the end panels to be swung through 180°.

When it is desired to use this auxiliary section as a garage, the roof and outer wall panels are swung out and supported in substantially the positions shown in Fig. 2, the floor is then lowered and the end panels swung about their hinges 140 sufficiently far to permit the auxiliary floor panel to be swung back up to vertical position.

Inasmuch as these end panels may be moved through 180°, they will serve as closures for the auxiliary structure and it will be clear that the auxiliary floor section will constitute a partition between the main body section and the garage housing.

The specific embodiment shown in the accompanying drawings and described above, is merely illustrative of the generic inventive concept defined in the sub-joined claims. Many other and further modifications will be apparent to those skilled in the art.

What is claimed is:

1. In an expandible building structure, a main body portion, an expandible roof section hinged at one of its edges to said main body portion, an outer wall panel hinged at one of its edges to said roof section, a brace member extending from the floor of said main body section to said outer wall section, means for locking said brace member to the floor section of said main body portion and to said outer wall section, and a foldable floor panel supported by said brace member.

2. In an expandible building structure a main body portion, an expandible roof section hinged at one of its edges to said main body portion, an outer wall section hinged at one of its edges to said roof section, means for supporting said outer wall section in extended position whereby the same serves to support said expandible roof section, a floor section pivotally connected to said main body section, a brace member extending from said main body section to said outer wall section and secured to said sections, said brace member serving to support said expandible floor section in extended position.

3. In an expandible building structure, a main body portion, an extensible roof section hinged at one of its edges to said body portion, an outer wall panel hinged at one of its edges to said roof section, a brace member extending from the floor of said main body section to said outer wall section, means for locking said brace member to the floor

section of said body portion and to said outer wall section, a foldable floor panel supported by said brace member and end wall sections hinged to said body portion adapted to mate with said roof section, outer wall section, and floor section to reinforce and strengthen said structure. 5

WILLIAM B. STOUT.
